UNITED STATES PATENT OFFICE.

OTTO E. BLACK, OF DAYTON, OHIO, ASSIGNOR TO THE LUCAS-MINER TOOL AND PRODUCTION COMPANY, OF DAYTON, OHIO, A CORPORATION OF OHIO.

DESIGN FOR A RADIATOR-CAP.

58,874.

Specification for Design.

Patented Sept. 6, 1921.

Application filed June 7, 1921. Serial No. 475,744. Term of patent 7 years.

To all whom it may concern:

Be it known that I, OTTO E. BLACK, a citizen of the United States of America, residing at Dayton, county of Montgomery, State of Ohio, have invented a new, original, ornamental Design for a Radiator-Cap, of which the following is a specification, reference being had to the accompanying drawing, forming a part thereof.

In the drawing, Figure 1 is a front elevation illustrating the relation to a motor me-

ter and radiator, and Fig. 2 an end elevation of the radiator cap, showing my new design.

I claim:

The ornamental design for a radiator cap as shown.

In testimony whereof, I have hereunto set my hand this 31 day of May, A. D. 1921.

OTTO E. BLACK.
